UNITED STATES PATENT OFFICE.

WILLIAM WENDERHOLD, OF NEW YORK, N. Y., ASSIGNOR TO CRU PATENTS CORPORATION, A CORPORATION OF NEW YORK.

UNIVERSAL PROJECTOR-SUPPORT.

1,383,683.

Specification of Letters Patent. Patented July 5, 1921.

Application filed June 9, 1917. Serial No. 173,763.

To all whom it may concern:

Be it known that I, WILLIAM WENDERHOLD, a citizen of the United States, residing at New York city, in the county and State of New York, have invented certain new and useful Improvements in Universal Projector-Supports, of which the following is a clear, full, and exact description.

The object of this device is to provide a structural support for a motion picture projector and lamp house that is easily adjustable in all directions.

Another object is to provide the structure with a power device in such manner that the distance between the driving and the driven shafts remains constant and unaffected by the adjustments of the support.

Another object is to provide receptacles in the structure that may be used to receive tools, supplies, and carbons as may be needed.

Referring to the drawings,

Figure 1 is a side elevation.

Fig. 2 is an opposite side elevation.

Fig. 3 is the same side elevation showing part thereof tilted.

Fig. 4 is a top view of the device.

Fig. 5 is a view of another type of pedestal instead of the four-legged type shown in Figs. 1, 2, 3, 4 and 6.

Fig. 6 is a partial side elevation of the four-legged pedestal.

As shown in Fig. 1, the legs 1 support the receptacle frame 2, which frame can be lowered or raised on the legs 1, since they are slidably clamped therein by screws 3 (see Fig. 4). The frame 2 contains the three drawers or magazines 4, 5 and 6, and supports the pivot bracket 7 upon its pivot hub 2^a (see Fig. 6) which bracket is locked onto frame 2 in curved slots 8' and 9' by bolts 8 and 9, and adjustably clamped upon the pivot hub 2^a by the bolts 10 and 11 (see Figs. 2 and 4). The pivot bracket 7 supports the take-up reel magazine 12, the center of the reel supporting shaft 13 being the pivot point of the magazine 12 in the bracket 7. A worm sector 14 is fastened to bracket 7 by four screws 15. The worm 16 on shaft 17 is fastened on the magazine 12 by the bearing brackets 18 and 19. The worm may be operated by the handle knob 20 and when the desired position of the machine is obtained, the screws 21 will tighten the magazine 12 on the pivot bracket

7. The clamps 22 and 23 can also be tightened by the bolts 24 and 25. These clamps are attached to the magazine 12. On top of the magazine 12 is mounted the projecting head 26. The pulley 27 drives the take-up shaft 13 by means of belt 28. The pulley 29 drives the mechanism of the projecting head and is driven by means of belt 30, the driving power being derived from the variable speed device 31, as disclosed in my application #165082, filed April 28th 1917, the variable speed device being supported by bracket 32, which is fastened to the pivot bracket 7 by screws 33, 34 and 35, and consequently will move with the bracket 7 only. On the bracket 32 is also mounted the electric motor 36 which drives the speed device 31 by means of coupling 37. The variable speed device is controlled by handle knob 31^a. The axis of the driving pulley 38 on the speed device is in central alignment with the reel support shaft 13, and the pulley 13^a, (see Fig. 4) and therefore any tilting of the magazine 12 does not alter the distance between the driving and driven elements 27, 29 and 38 and 13^a, which feature is of great importance and convenience to the operator. The triangular bracket 39 is also securely fastened to the magazine 12 and supports the lamp housing 40.

The receptacle frame 2 having four legs can be replaced by one support 41, as shown in Fig. 5, being also provided with receptacles 42 and 43 in bracket 44 which can be revolved around the pivot point 41^a.

Considerable changes can be made in the structure without departing from the principle of providing adjustment in all directions without altering the distance between the motive power and the driven elements 95 and providing the structure with receptacles of usefulness as herein described.

What I claim as my invention is:

1. A supporting structure for a projecting apparatus consisting of a main base, a second base pivotally supported thereon upon a vertical axis, magazines or drawers in the main base, a source of power supported by the second base, a film reel magazine pivotally mounted upon said second base, a horizontally disposed reel shaft for actuating said reel magazine, said reel shaft forming the pivotal axis for said reel magazine, said shaft being disposed in longitudinal alignment with the driving element of the driving

power source, means to pivotally adjust said second base and said reel magazine, and a projecting apparatus supported by said reel magazine.

- 5 2. A supporting structure of a projecting apparatus comprising a main base having legs, a second base pivotally mounted upon a vertical axis on said main base, a horizontally disposed film reel supporting shaft 10 mounted in said second base, a film magazine pivotally supported on said shaft, a motor also carried by said second base, a driving element connected to said motor and arranged in longitudinal alinement with 15 the film reel supporting shaft, and means to rotatively adjust said film magazine about its horizontally disposed supporting shaft, and means for adjusting said second base about its vertically pivotal axis.
- 20 3. A supporting structure for a projecting apparatus consisting of a main base, a member mounted thereon for axial movement on a vertical axis, and means for adjusting said member about said axis, a horizontally disposed shaft mounted in said member, a reel magazine pivotally mounted upon said shaft, a worm gear connected to said magazine, means engaging said worm gear to rotatively adjust said magazine upon its supporting shaft, a projecting apparatus carried by said magazine; a motor mounted on 25 said first-named member, the driving ele-
- 30

ment of said motor being arranged in line with the horizontally disposed reel magazine supporting shaft, and means to transmit power from said motor to the projecting apparatus.

4. The herein described device for supporting a projecting apparatus, consisting of a rigid base having magazines, an upright member pivotally mounted on said base, a source of power, a bracket on said base and forming a support for said source of power, a projector, a pivotally mounted film reel magazine arranged to support said projector, and means to adjust said magazine.

5. In a supporting structure for projection apparatus, the combination of a main supporting base, a secondary base adjustably mounted upon said main base, a horizontally disposed film reel supporting shaft mounted upon said second base, a film magazine pivotally supported on said shaft, a motor carried by said second base, a driving element connected to said motor, and mounted in alinement with the film reel supporting shaft, and means to rotatively adjust said film magazine on its horizontally disposed supporting shaft.

Signed at the city of New York, New York, this seventh day of June, one thousand nine hundred and seventeen.

WILLIAM WENDERHOLD.
